INTERLOCKING SYSTEM FOR RAILROADS

Filed March 27, 1926

FIG. 1

UNITED STATES PATENT OFFICE

JAMES E. STEPHENSON, OF ROCHESTER, NEW YORK, ASSIGNEE TO GENERAL RAILWAY SIGNAL COMPANY, OF ROCHESTER, NEW YORK

INTERLOCKING SYSTEM FOR RAILROADS

Application filed March 27, 1926. Serial No. 97,911.

This invention relates to interlocking systems for railroads and more particularly to interlocking systems of the dynamic indication type.

In interlocking systems, it is quite common to have two traffic controlling devices so located with respect to each other and the routes or switches they control that both of such devices need not be operated at the same time, and more often such devices must not be operated at the same time. Under such circumstances, it is found economical, both as to interlocking mechanism and lever space, to operate both of such traffic controlling devices off of the same lever.

In accordance with the present invention, it is proposed to construct an interlocking lever usable in connection with dynamic indication apparatus so as to have a normal middle position and two reverse extreme positions, so as to make it in fact a three-position lever. More specifically, it is proposed to construct an interlocking lever having an indicating latch forcibly moved to its latching position as the lever is moved in either direction from its normal position, to provide a latch dog which is forcibly driven into its latch engaging position as the lever is moved from its normal middle position in either direction, and to provide the necessary contacts to complete the necessary control and dynamic indication circuits.

Other objects, purposes and characteristic features of the invention will appear as the description thereof progresses.

In describing the invention in detail, reference will be made to the accompanying drawings, in which:

Fig. 1 shows a novel interlocking system according to the present invention, wherein two signal circuits are controlled by a single lever and in which the principle of dynamic indication is employed;

Fig. 2 illustrates the lever shown in Fig. 1 to a larger scale; and

Fig. 3 illustrates a transverse section of the lever taken on the line 3-3 of Fig. 2 as viewed in the direction of the arrows.

In order to simplify the description of the present invention, the mechanism of the sig-

nals whereby dynamic indication current is generated has not been shown specifically and for this reason it is considered expedient to briefly review the principle of dynamic indication. In interlocking practice, it is considered highly essential that the indication current shall, if possible, be distinctive from the control current so that the indication current cannot readily, or even possibly, flow as a result of a cross, or the like. Also, the source of indication current, if possible, should not be present until the traffic controlling device has responded to the changed position in the lever at the tower. In accordance with the dynamic indication principle, both of these essentials are taken care of by requiring the traffic controlling device itself to generate the dynamic indication current after it has practically completed its movement in response to a change in the position of the lever; and further, in having this traffic controlling device generate a current of distinctive polarity, distinctive phase, if alternating current is used, or the like. For further information regarding dynamic indication systems of the type mentioned reference may be had to the patent to Frank Benedict No. 1,533,357 April 14, 1925 and the application of P. X. Rice Ser. #624,265 filed March 10, 1923.

If the lever in such a dynamic indication system controls a signal, as is the case in the embodiment of the invention illustrated in Fig. 1, the signal is operated to the clear position by the application of current to its control wire, and if the signal is to be returned to its normal position, the source of energy is disconnected, from the control wire, and the control wire is connected to an indication magnet on the lever. When the signal has almost completed its return movement, a circuit is completed through this indication magnet in which current flows, due to regeneration as a result of the signal moving, by gravity, a spring, or both, to its normal danger position; the dynamically-generated current flowing in the same direction through the control wire as that flowing in the control wire when the signal is cleared.

Structure

Referring to Fig. 1, the invention has been shown in connection with a lever L controlling the entering (westbound) signal Z at the approach to a siding 1, the leaving (eastbound) signal Z¹ of such siding, and the leaving (eastbound) signal Z² of the main track 2 of such siding, this siding including a manually or power operable switch S. The control wire 3 leads directly to the signal Z, and the control wire 4 leads to the signal Z² or the signal Z¹ through wires 5 and 6, respectively, depending on the position of the switch box 10 contact 7 controlled by the switch S.

Referring to Fig. 2, the control lever L comprises a main bar or lever 10 which is slidably supported between the frame pieces 11 and 12, (see Figs. 2 and 3), and is held down by a top plate 13 upon the interlocking frame portions 14 and 19.

This lever L is connected by a rod 15 to a contact block 16 for controlling the control and dynamic indication circuits, more specifically described hereinafter. This main bar 10 is thus slidably supported for endwise movement, and by the provision of the Z-shaped cam slot 17 is adapted to move the roller 18 up and down as the lever is pulled out and pushed in, respectively. This roller 17 operates the usual tappet bar of the interlocking machine, familiar to those skilled in the art.

The lever 10 has notches cut in its lower portion, leaving a lock lug 20, latch lugs 21 and 22, and a cam operating lug 23. Directly below this lever portion 10 and in the main frame of the interlocking machine is mounted an indication latch 25, pivotally supported by the pin 26, and spring pressed to its normal position as shown by the spring 27, this latch being adapted to be locked in its abnormal position by the indication dog 30 pivotally supported at 31 and spring pressed to its latch engaging position by the free end of the same spring 27. Directly below the indication dog 30 is an indication magnet IM, having an armature 33, which magnet if energized operates the latch to its disengaging position through the medium of a pin, as shown. Directly in back of the indication dog 30 is supported an indication cam 35, which is pivotally supported at 36, and is spring pressed to its normal position by the spring 37 contained on the spring plunger 38 slidably supported in the hole 39.

The mechanism just described is the well known indication locking mechanism which may be automatically unlocked by the indication magnet. In addition to this locking mechanism, there is provided a lever latching means which is manually controlled by turning the handle 40. In the particular arrangement shown, this handle 40 is fixed to the 60 rocking plunger 41 by a pin or screw 42. This

handle 40 is normally held in its upright position by a spring 43, secured within the hollow portion of the rear end of the lever 10, and having its other end fastened through the head of a screw 44 fastened in the rocking plunger 41. This rocking plunger also has a collar 45 pinned thereto to prevent endwise movement thereof. To the upstanding portion 13^a of the top plate 13, is secured by screws 51 and 52, the slot structure 50, of a bayonet slot arrangement. This slot structure 50 (see Fig. 3) contains a hole through which the rocking plunger 41 is adapted to slide as the lever 10 is moved back and forth, a keyway 54 being provided to allow one or the other of the keys 55 and 56 fixed to the plunger 41, to slide therethrough, depending on whether the handle 40 is tilted toward the right or toward the left, and whether the handle is pulled or pushed from its normal position. In order to aid the operator in tilting the handle 40 to the proper inclined position to register the key 55 or 56, as the case may be, with the keyway 54, lips 50^a and 50^b extending from the structure 50, have been provided, the upstanding portion 13^a being hollowed out to provide clearance for the lip 50^a.

Operation

If the operator wishes to clear the signal Z, he turns his lever toward the right and then pushes the same. This causes the latch lug 22 to push the indication latch to its locked position, so that the projection 25^a thereof moves upward on the left side of the lock lug 20. Upon further movement of the lever toward the right, the lock lug 20 engages the indication cam 35, thereby causing it to operate the indication dog 30 (if this has not already been operated by the end of spring 27), thus assuring that the indication latch is in its locked position. When the lever has finally reached its extreme right hand position, a circuit is completed from the terminal B of a suitable source of energy, contact 57 of the cross-protection relay, wires 58 and 59, through contacts 60 and 61, wire 3, the operating motor of the signal Z, to a common return wire C connected to the other side of said source of energy. This causes the signal Z to assume its clear or proceed position.

After the train has passed the signal, the operator should not be able to return the lever to its normal position, unless there is assurance that the signal Z has responded and again assumed its normal danger position. As the operator moves his lever from the extreme right hand position toward the left, the lock lug 20 engages the cam 35 and again rocks this cam to a position under the latch 25; but this operation of the cam 35 is, however, incidental and unnecessary, since the dog 30 was previously forced to its engaging position. Further movement of the lever to-

ward the left causes the lock lug 20 to engage the projecting portion 25^a of the indication latch 25, so that further movement of the lever is prevented. In this position of the lever, the roller 18 is still in its lower position and the lever L still locks conflicting levers of the interlocking machine.

In this position of the lever, however, an indication circuit is completed which may be traced as follows:—beginning at the common return wire C, the signal mechanism of the signal Z, wires 3 and 63, contacts 64 and 65, wires 66 and 67, coils of the indication magnet IM, wire 68, cross-protection relay CR, wire 69, to the common return wire C from which we started. When the signal Z has almost reached its danger position, the mechanism of the signal completes a dynamic indication circuit, whereby the motor of the signal Z generates current which flows through the indication circuit just traced and causes operation of the indication magnet IM, this current being in a direction (assuming a direct current system) so as not to operate the cross-protection relay CR. This cross-protection relay CR, in a direct current system, is a polarized device, and trips the contact 57 only if current flows as a result of the application of the B terminal to a part of the circuit such as the wire 67. Operation of the indication magnet IM causes the dog 30 to be moved out of engagement with the latch 25, allowing the spring 27 to operate the latch to its non-engaging position, whereby the operator is permitted to move the lever still further toward the left to its normal position, in which position the roller 18 unlocks all conflicting levers.

If the operator desires to clear either the signal Z¹ or the signal Z², depending on the position of the switch S, to allow a train to pass, he will tilt the handle 40 toward the left, thereby allowing the key 56 to enter slot 54, after which he may pull out the lever toward the left, and in so doing cause the left hand end of the latch 25 to be forced down by the latch lug 21, this latch lug 21 engaging the indication latch 25, thereby moving this latch 25 to its locking position. A slight further movement of the lever causes the cam operating lug 23 to engage the indication cam 35, the operation of which mechanically forces the indication dog 30 into its engaging position, if spring 27 has not already done so. As the lever L is moved to the extreme left hand position, a circuit for the signal Z² (assuming the switch S to be in its normal position), may be traced as follows:—beginning at the terminal B, contact 57 of the cross-protection device CR, wires 58 and 62, contacts 70—65; wires 4 and 71, switch box contacts 7, wire 5, operating mechanism of the signal Z² to the common return wire C. The completion of this cir-

cuit causes clearing of the signal Z² permitting a train to proceed from left to right on the main track 2.

Let us now assume that the train has passed signal Z² and that the operator wishes to move his lever to the normal position to unlock conflicting levers locked while the lever is in the left hand position. As the lever is moved from the extreme left hand position toward the right, the lock lug 20 engages the lug 25^a of the latch 25, thus preventing further movement of the lever toward the right. In this position, however, an indication circuit is completed which may be traced as follows:—beginning at the common return wire C, mechanism of the signal Z², wire 5 contact 7, wires 71, 4 and 72, contacts 60 and 73, wires 74 and 67, winding of the indication magnet IM, wire 68, cross-protection relay CR, wire 69 back to the common return wire C. When the signal Z² has almost reached its danger position, by reason of the return of the signal to its stop position by the action of gravity or a spring or both, this indication circuit is completed in the signal mechanism, and this signal mechanism causes indication current to flow which operates the indication magnet IM. The flow of this indication current raises the armature 33 forcibly for an instant, and in so doing disengages the dog 30 and allows the latch 25 to again assume its normal position. As the lever is returned to its middle normal position, the roller 18 operates the tappet bar to a position to unlock all conflicting levers. If the switch S is open when the lever is moved to the extreme left position the signal Z¹ is obviously cleared instead of signal Z², the operation of which need not be specifically considered.

It should be noted that if the wire 67 should accidentally, due to a cross, or the like, (when lever L is in the position shown in Fig. 1) be connected to the terminal B of the battery or other source of energy, the current due to such connection could flow to the signals Z and Z² and also through the indication magnet and the cross-protection relay. This flow of current, being in a direction to operate the cross-protection relay, would actuate the cross-protection relay very quickly and the terminal B would be entirely disconnected from the interlocking system before the signals could be cleared by such unauthorized current. The raising of the latch 74 as a result of the flow of this unauthorized current, allows the spring 75 to move the contact 57 to its open position, where it will remain until it is manually restored by the operator.

Having thus shown and described one specific embodiment of an interlocking system of the dynamic indication type in which a single three-position lever may control a plurality of traffic controlling devices, it is de-

sired to be understood that the specific arrangement illustrated has been shown for the purpose of illustrating the nature of the invention rather than its scope, and that various changes, modifications and additions may be made to adapt the invention to a system including a plurality of switch machines or other traffic controlling devices without departing from the scope of the invention or the idea of means underlying the same.

What I claim as new is:—

1. In an interlocking system, the combination with a plurality of traffic controlling devices of a single lever for controlling the same, a latch dog associated with said lever, said lever being movable into either extreme position from its normal middle position and being locked by said latch dog against movement thereof toward the middle normal position, and an indication magnet for striking said latch dog so as to move it out of its engaging position when a dynamic indication is received from one of said traffic controlling devices to permit said lever to be returned to its normal position.

2. In an interlocking system, the combination with a lever having an indication latch, of a lock dog for locking said latch and a cam for forcing said dog into engagement with said latch, said lever having a middle normal position and two extreme positions and having lugs for forcibly operating said latch and said cam into their active positions when said lever is moved to either extreme position from the middle position, an indication magnet which if momentarily energized operates said lock dog to disengage said latch, and two electrically operated traffic controlled devices capable of generating a dynamic indication current when they have almost completed their operation in response to a change in the position of said lever toward the normal position.

3. A lever for interlocking machines comprising, a lever bar slidably supported in a frame, a rock plunger rockably supported on said lever bar and having its free end slidably supported in stationary means having a slot, a handle for said rocking plunger, and means associated with said rocking plunger for preventing said lever from being moved slidably unless said handle is first tilted from its normal position.

4. Locking means for reciprocal levers of interlocking machines comprising, a shaft secured to such lever in a manner to permit it to be rocked about its axis and so as to have its axis substantially parallel to the direction in which said lever may be reciprocated, stationary means in which said shaft is adapted to slide having a slot therein, and a key projecting out of said shaft and out of alignment with said slot when said shaft is in its normal position, whereby said shaft

must be rotated to an extent to line said key up with said slot before said lever may be moved in a certain direction.

5. Locking means for reciprocal levers of interlocking machines comprising, a shaft secured to such lever in a manner to permit it to be rocked about its axis and so as to have its axis substantially parallel to the direction in which said lever may be reciprocated, stationary means in which said shaft is adapted to slide having a slot therein, and two keys projecting out of said shaft on opposite sides of said stationary means when said lever is in its middle position, said keys being out of alignment with each other, whereby said shaft must be rocked to different positions to permit said lever to be pulled and pushed respectively.

6. An interlocking lever comprising, a lever bar supported for slidable endwise movement, a rock shaft supported by said lever bar against endwise movement with respect to said lever bar and so as to have its axis parallel to the direction of movement of said lever bar, a handle on said rock shaft for reciprocating said lever bar, stationary means in which said shaft may slide provided with a slot therein, and a key projecting from said shaft out of alignment with said slot so that said handle must be tilted to permit said key to enter said slot before said lever bar can be moved in a certain direction.

7. An interlocking lever comprising, a lever bar supported for slidable endwise movement, a rock shaft supported by said lever bar against endwise movement with respect to said lever bar and so as to have its axis parallel to the direction of movement of said lever bar, a handle on said rock shaft for reciprocating said lever bar, stationary means in which said shaft may slide having a slot therein, and two keys projecting from said shaft on opposite sides of said stationary means when said lever is in its middle position, said keys being out of alignment with each other, whereby said handle must be tilted in one direction or the other as the lever bar is operated in one direction or the other.

8. In an interlocking system, a three position lever for controlling two electrically operated traffic controlling devices, the middle position of said lever putting both of said devices in their normal condition, movement to one extreme position of said lever putting one of said devices in its abnormal condition, and movement of the lever to its other extreme position putting the other of said devices in its abnormal condition; and manually operable mechanical means for preventing said lever from being moved from one extreme position to the other extreme position by a single movement.

9. In an interlocking system, a three position lever for controlling two electrically

operated traffic controlling devices, the middle position of said lever putting both of said devices in their normal condition, movement to one extreme position of said lever putting 5 one of said devices in its abnormal condition, and movement of the lever to its other extreme position putting the other of said devices in its abnormal condition; locking means for locking said lever against movement from either extreme position to the middle position; and means for unlocking said locking means by current generated dynamically by one or the other of said traffic controlling devices depending on from which 10 extreme position said lever has been moved to the middle position.

10. In an interlocking system, a three position lever for controlling two electrically operated traffic controlling devices, the normal 20 position of said lever putting both of said devices in their normal condition, movement of said lever to one extreme position putting one of said devices in its abnormal condition, and movement of said lever to its other extreme position putting the other of said devices in its abnormal condition; and means for checking said lever against movement to the normal position by dynamic indication current derived from the traffic controlling device last changed.

11. In an interlocking system of the electrically operated dynamic indication type, a three position lever for independently operating two traffic controlling devices, and 35 means for checking said lever against movement to the normal position by dynamic indication current derived from the traffic controlling device last operated.

12. In an interlocking system, in combination, a plurality of traffic control devices capable of generating indication current, a single control lever for the same having a normal and a plurality of reverse positions, and latch means, responsive to said indication current, for preventing movement of the lever to the normal position.

13. In an interlocking system, in combination, a plurality of traffic control devices, a single control lever for the same having a normal and a plurality of reverse positions, latch means for preventing movement of the lever to the normal position, and release means for said latch means, operable by dynamic indication current, for allowing movement of the lever to its normal position.

14. In an interlocking system, in combination, two traffic control devices, a single lever for controlling the devices, energizing circuits for said devices, a check relay controlling said circuits, and energizing circuits for the check relay including contacts controlled by said single lever and portions of said energizing circuits for the control devices.

15. In an interlocking system, a plurality 65 of traffic controlling devices, a single lever

for controlling said devices and having normal and reverse controlling positions, and means, operable by current generated in accordance with the condition of said controlling device, for checking said lever against movement to normal position.

16. In an interlocking system, a plurality of traffic controlling devices, a single lever for controlling said devices and having normal and reverse controlling positions, and 75 means to check the lever against movement to normal position controlled by dynamic indication current produced by one of the traffic controlling devices.

17. In an interlocking system, a plurality of traffic controlling devices, a single lever for controlling said devices and having normal and reverse controlling positions, and means to check the lever against movement to normal position controlled by dynamic indication current produced by traffic controlling means.

18. In an interlocking system, a plurality of traffic controlling devices, having means for generating an indication current upon movement to operated position, a single lever for separately controlling said devices and detent means for said lever responsive to said current.

In testimony whereof I hereby affix my signature.

JAMES E. STEPHENSON.
